Charles Parker, who has notified his intention to become a citizen of the United States.....

• No. 283. "Improvement in a machine for drawing Ropes" Date of Patent... 13th April 1836
Certificate of Drawing sent 13th April 1836.

The Schedule referred to in their Letters Patent and making part of the Specification containing a description of the several parts of Charles Parker himself, of his Improvement in the Machine for drawing Ropes.

To all to whom these shall come: I do hereby declare that I, Charles Parker of the City, County and State of New York, have invented a new and useful machine and that the following is a full and exact description thereof. Figure 1 in the annexed represents a profile view of the entire machine in its working position on the rope A. The drawing Reel C is so constructed as to move clear of the circular side of the reel D. The circular handle D, being placed horizontally connects the small end or end of rope from the body of the reel and lets it off upon the rope or cable to be drawn by being made to revolve round the body of the rope or cable, clearing at the same time, the side of the reel D. The drawing Reel pushing the reel along until the service is completed the weight of the suspended figure and looped in a groove over the outer end of the reel body is sufficient to regulate the motion of the machine and to keep it steady. The letter H designates the position of the hinge upon which the reel opens to be clasped around the rope or cable intended to be drawn, in which position the Reel is turned by the Hooks and staples represented on the upper curve of Figure 1. This Figure 2 represents a front view of the

April 13 1836

off side of the machine near the weight. It is showing the knot or handle by which the service rope is to be secured upon the steel when the latter is suspended upon a pulley for that purpose. The letter *b* in Figures 2, 3, designates the circular end of the steel body to which the regulating weight is attached. The yellow inside circle shows the positions of the bushings which are constructed to reduce the internal diameter of the steel in order to graduate it to one or more different sized ropes or cables; the letter *c* in Figures 2, 3, designates the triangular opening necessary to be left in the circular sides of the machine in order to admit of its being unfastened. It is a slide to be secured in its position by blocks and staples when the machine is in working order. Figure 3 indicates by letter *c* the two parts of the graduating bushings which can be made of any required dimensions. They are to be placed inside the steel body, and secured in position by two blocks and staples on the weight side or end of the machine. Figure 4 shows the old starting mallet with the additions and improvement made by the present application. It is intended that this machine shall be constructed of all suitable woods and metals, or a combination of both materials. The manner of using this machine is as follows: when after the rope to which to be secured is hauled taut in the usual way the steel is to be unfastened and fitted upon the ropes or cables bearing the service end; the starting mallet, placed in a perpendicular position upon the ropes close against the body of the steel, with the service cable run through the tubular part of the handle with force enough

turns around the butt of the mallet and the rope to be wound, thereby causing the mallet to revolve around the cable and reel, the driving cord will be left upon the cable in proportion as the reel is revolved, the reel at the same time moving forward in a ratio with the motion of the mallet. It will then be seen the motion most uniform the hand of the workman should be applied to the angle action. The tubular and solid parts of the mallet handle must. By using this machine the labour of the person on every rope to be strained is saved inasmuch as it certainly dispenses with the present process of casting the cable, driving and winding the rope.

What I claim as my own invention and not previously known in the above described machine is as follows to wit: every part thereof except the butt and perpendicular or solid handle of the driving mallet; having the body and sides of the reel; the driving or spinning the same into two parts joined by a hinge and fastened by hook and staple; the handle for turning the reel when set on the rope or cable in order to wind the driving cord upon the reel; the application of the cordage to regulate the motion; the bushings in two parts to regulate the internal diameter of the reel; the tubular part of the driving mallet handle to cover the driving cord clear of the circular outer side of the reel; the moving slide for closing the triangular opening in the sides of the reel; and the general application of all the parts of the machine and driving mallet as a whole to be joined and constructed of wood or metal, &c.

combination of both materials, so that it would be business
of serving & splicing cables in order to increase their
strength and durability.
